Patented May 2, 1916.

2 SHEETS—SHEET 2.

UNITED STATES PATENT OFFICE.

EARL W. YARLOTT, OF MONTPELIER, OHIO.

INTERNAL-COMBUSTION ENGINE.

1,181,558.

Specification of Letters Patent.

Patented May 2, 1916.

Application filed November 7, 1913. Serial No. 799,727.

To all whom it may concern:

Be it known that I, EARL W. YARLOTT, a citizen of the United States, residing at Montpelier, in the county of Williams, State of Ohio, have invented certain new and useful Improvements in Internal-Combustion Engines; and I do hereby declare the following to be a full, clear, and exact description of the invention, such as will enable others skilled in the art to which it appertains to make and use the same.

This invention relates to internal combustion engines and has for an object to provide an improved valve mechanism in which a single revoluble valve operates to connect the firing ends of two or more cylinders in the proper sequence with the fuel supply and with the exhaust.

A further object is to provide a valve mechanism in which the valve will be directly exposed to atmospheric pressure so as to be air cooled as well as water cooled, the valve being constructed and arranged to admit of an unobstructed free exhaust of the burnt gases directly from the valve itself into the atmosphere, thus eliminating back pressure.

A further object is to provide a novel and extremely simple and compact distributor head including a single valve cage and separate passages leading therefrom to respective cylinders, the valve rotating in said valve cage and effecting the proper distribution of the fresh gases and proper taking up of the burnt gases at the proper periods from the cylinders silently and with precision.

With the above objects in view the invention consists of certain novel details of construction and combination of parts hereinafter fully described and claimed, it being understood that various modifications may be made in the minor details of construction within the scope of the appended claim.

In the accompanying drawings illustrating this invention: Figure 1 is a side elevation of a four cylinder four cycle gas engine embodying my improvements. Fig. 2 is a vertical section taken on the line 2-2 Fig. 1. Fig. 3 is a cross sectional view on the line 3-3 Fig. 1. Fig. 4 is an enlarged plan view of the valve detached. Fig. 5 is a cross sectional view on the line 5-5 Fig. 4. Fig. 6 is a cross sectional view on the line 6-6 Fig. 4.

Referring now to the drawings in which like characters of reference designate similar parts, 10 designates a four cylinder four cycle gas engine, the inner cylinders being spaced apart to provide a space for the reception of a shaft 11 which is provided at its upper end with a valve 12 that will be presently more fully described. The lower end of the shaft 11 is journaled in bushings 13 and 14 preferably of brass arranged in bored openings in a solid section 14 of the crank case as shown in Fig. 2 and adjacent to said lower end the shaft 11 has fast thereon a worm wheel 15 which meshes with and is driven by a worm gear 16 fast on a countershaft 17 driven from the crank shaft 4 by means of gears 18 and 19 fast respectively on the crank shaft 4 and the countershaft 17. These gears are so proportioned relatively to each other and the worms 15 and 16, that the rotary valve shaft 11 is driven at one-half the speed of the crank shaft 4, this being necessary to produce an engine of the four-cycle principle. The shaft 11 is also made in two sections which are connected together by a universal joint 20 the object of which is to prevent any cramping or binding of the valve 12 in its seat in the cage.

The valve cage 21 is formed as an integral portion of an extremely simple and compact distributor head best shown in Figs. 2 and 3. By referring to Fig. 2 it will be seen that the valve cage is bored and tapered as shown at 22 to snugly receive the valve 12, the cage being also rabbeted as shown at 23 to form an annular shoulder against which the inner and smaller end of the valve is seated. By now referring to Fig. 3 it will be seen that there is a series of passages 25, 26, 27 and 28 which lead off from corresponding ports 29, 30, 31 and 32 formed in the circular wall of the cage 21, these passages communicating with respective cylinders 8.

The passage 25 communicates with a port 33 in one cylinder, the passage 26 communicates with a port 34 in another cylinder, the passage 27 communicates with a port 35 in another cylinder and the passage 28 communicates with a port 36 in the remaining cylinder, there being as many passages as there are cylinders and ports, the object being to lead the fresh gas successively to each of the cylinders and also exhaust the burnt gases successively therefrom. Furthermore,

- the multiple distributor head is water jacketed as indicated at 37 to keep the valve cage, valve and passages cool during the operation of the engine. There is an intake pipe 38 5 with which any suitable carburetor or mixing valve may be associated and through which the fresh gas is admitted to the valve and passages referred to and subsequently to the combustion chambers of the cylinders.
- 10 At the top the valve cage is left open as shown at 39 to enable the valve 12 to be easily placed therein and removed therefrom and also to admit of the free and unobstructed exhaust of the gases through and 15 from the valve. The valve 12 is formed at one side with an L-shaped inlet port 40 the receiving end 41 of which is located at the bottom of the valve while the discharge end 42 thereof opens out through one side of the 20 valve thus adapting the gas to pass upwardly through the valve and out through the side thereof so as to find its way into one of the passages above referred to as leading to the combustion chambers of the cylinders.
- 25 At another point the valve is provided with an L-shaped port 43 the receiving end 44 of which is adapted to register with either one of the ports 29 to 32 above referred to and the discharge end 45 of which opens 30 through the top of the valve. Therefore, the exhaust gases received from the cylinders of the engine through the passages 25 to 28 pass through the L-shaped port 40 of the valve and exhaust directly to the atmosphere upon leaving the valve, thus eliminating 35 back pressure.
- By reference to Fig. 4 it will be observed that the vertical portions of the L-shaped 40 passages are elongated so as to extend approximately half way around the axis of the valve and it will also be noted by reference to Figs. 3 and 4 that the portions 42 and 44 of the L-shaped passages are elongated circumferentially of the valve in order to give 45 the necessary period of time to provide for the intake and exhaust of the gases passing through the valve.
- From the foregoing description taken in 50 connection with the drawings it will be noted that the fresh gas or mixture passes into the cage and travels in an upward direction through the valve into the pas-

sages leading to the cylinders while the exhaust gas enters the valve and passes upwardly and outwardly through the valve and 55 directly therefrom into the atmosphere, said upward movement of the gas adding materially to the smoothness of operation and efficiency of the motor and also assists in reducing back pressure to a minimum. 60

It will be noted especially that the valve has its top face exposed to the atmosphere so that the valve is air-cooled during its rotation while at the same time the exhaust gases escape direct into the atmosphere so 65 that heating of the valve will be reduced to a minimum and thus the smooth and effective operation of the engine will at all times be assured. By referring to Fig. 3 it will be noted that the entire distributor head is 70 water cooled from the water jacket of the engine so that internal heating of the parts is reduced to a minimum.

What is claimed, is:

In an internal combustion engine, a cylinder casing having a valve seat formed in the upper portion thereof connected at various points in its side wall to communicate with the different cylinders of the engine, the said casing being constructed to provide a chamber below and communicating with the lower portion of said valve seat, a valve mounted for rotation in said seat, the upper and lower faces of said valve communicating with the atmosphere and chamber respectively, the said valve being provided with diametrically and inversely disposed L-shaped passages, the ends of one of which communicate with the side wall and upper face respectively of said valve, and the ends 90 of the other of said passages communicating with the side wall and bottom face respectively of said valve, a shaft connected at one end to said valve and being geared at its opposite end to the crank shaft of said engine, and means for admitting gas to said chamber. 95

In testimony whereof, I affix my signature in the presence of two witnesses.

EARL W. YARLOTT.
